UNITED STATES PATENT OFFICE.

GREGORY C. DAVISON, OF THE UNITED STATES NAVY.

HEATER FOR TORPEDOES.

No. 858,156.

Specification of Letters Patent.

Patented June 25, 1907.

Application filed November 24, 1906. Serial No. 344,977.

To all whom it may concern:

Be it known that I, GREGORY C. DAVISON, lieutenant commander, United States Navy, a citizen of the United States, and stationed 5 at Newport, in the county of Newport and State of Rhode Island, have invented certain new and useful Improvements in Heaters for Torpedoes; and I do hereby declare the following to be a full, clear, and exact description 10 of the invention, such as will enable others skilled in the art to which it appertains to make and use the same.

My invention relates to improvements in heaters for torpedoes, and the object of my 15 invention is to produce a simple, automatically operated heater which will thoroughly heat all of the air used in the propulsion of automobile torpedoes.

With this object in view, my invention 20 consists in the construction and combinations of parts as hereinafter described and claimed.

In the accompanying drawings; Figure 1 is a side view of a torpedo, some of the internal parts being shown in dotted lines. Fig. 2 is a longitudinal cross section of a part of the body of a torpedo on a larger scale showing my invention, and Fig. 3 is a cross section of the same taken through the stove.

In ordinary torpedoes, air is compressed 30 into the air chamber thereof, usually to a pressure of about 2250 pounds to the square inch. From a pound of this compressed air at the ordinary temperature of 70 degrees F., an energy of about 15,000 foot pounds may 35 be developed. If, however, the temperature of the air is raised to about 600 degrees F., the same amount will develop 30,000 foot pounds of energy. This fact has already 40 been taken advantage of in automobile torpedo construction, but the heaters now in use are objectionable in that the feed of the fuel is not uniform, the temperature of the air delivered to the engine is not constant as it 45 gradually rises from the beginning of the run until the middle of the run and then gradually falls, so that the maximum benefit from heating the air is not obtained. Furthermore, in the ordinary construction the walls

of the air flask are heated producing undesirable results in the nature of deterioration, and also in the loss of heat transmitted through the flask to the surrounding water. Furthermore, the heating of the air is not uniform, and much of the air escapes to the engine either in a cold state, or only partially heated.

It is the object of my invention to do away with these defects and produce a heater by which all the air delivered to the engine is evenly and completely heated from the beginning of the run to the end thereof.

In the drawings, *a* represents the torpedo, of a well known type, various parts of the interior mechanism being shown in dotted lines.

b and *c* represent the partitions screwed into internal annular projections *d* forming the air chamber into which air is compressed in the usual way.

e represents the thinner conical part of the torpedo attached to the rear of the air chamber, which is made with thicker walls to resist the heavy air pressure.

f is a partition arranged in the rear of the 75 partition *e* forming a chamber *d* in which chamber are located the reservoirs *h*, *i* and *j* for the fuel, preferably alcohol. These receptacles are preferably made in the form of hollow cylinders with closed ends. They are 80 arranged on different levels, as shown in Fig. 2.

k represents a pipe by which the receptacle *h* may be filled, and *m* and *n* represent pipes for the escape of air from the receptacles *i* 85 and *j*. These receptacles are all connected to a common delivery pipe *q*.

o represents a plug adapted to fit in a screw threaded projection *p* in the part *e*. By removing this plug alcohol may be poured 90 through the tube *k* into the receptacle *h*, and it, of course, will rise to the same level in the three receptacles *h*, *i* and *j* as indicated by the dotted lines in Fig. 2, the surplus air escaping through the pipes *m* and *n*.

The pipe *q* terminates in a jet burner *r*, which is located in a depression *t* in the bottom of the stove *s*, which is made circular in

7c

95

shape and held in position by the brackets *x* within the air flask. The stove *s* is provided with openings *u* for the air, and is connected by means of a pipe *v* to the engines. In the pipe *q* is located a valve *w* adapted to be operated by hand.

y represents an ordinary cordite fuse carried in a tube *z* which is provided with an ordinary or well known means for igniting the fuse when the torpedo is discharged. The torpedo is, of course, provided with the ordinary war nose, charge of explosive material, operating engines, screws, and steering means, but these form no part of my present invention.

The operation of the device is as follows. The valve *w* being closed, the air flask is charged with air under a heavy pressure in the usual manner, the receptacles *h*, *i* and *j* being previously partially filled with alcohol or some other inflammable fuel, and the plug *p* is placed in position. After the air chamber has been fully charged, the valve *w* is opened, and the air then bubbles up through the alcohol in the receptacles *h*, *i* and *j* until the pressure in the top of these receptacles is equal to the pressure in the air chamber. After the torpedo is discharged, the air at once begins to be delivered through the pipe *v* to the engines, and the cordite fuse *y* is ignited by the discharge. The pressure in the air flask immediately falls, whereupon the air confined in the receptacles *h*, *i* and *j* forces the alcohol through the pipe *q* through the jet burner *r*, where it is ignited by the cordite fuse *y*, thus heating all the air which enters through the holes *u* in the sides of the stove. It is obvious that all the air which goes to the engines must pass through the stove, so that it must become heated before it reaches the engines. Furthermore, the jet burner *p* sprays the alcohol giving better combustion and preventing the clogging of the pipe *q* by dirt.

An important feature of my invention is the arrangement of the three receptacles at different levels, as shown in Fig. 2. This is designed for the purpose of giving a practically constant feed of alcohol to the stove, which, of course, is the ideal condition. The amount of alcohol fed from each of the receptacles *h*, *i* and *j*, is, of course, practically the same per minute, but the amount of alcohol in the receptacle *j* is much less in quantity than it is in the receptacle *i*, so that this receptacle becomes empty of fuel much quicker than does the receptacle *i*, which in turn becomes empty of fuel quicker than the receptacle *h*. By these means, a practically uniform feed is obtained.

By the use of my invention practically all the objections to the present type of feeders are overcome.

Having thus described my invention, what

I claim as new and desire to secure by Let- 65 ters Patent, is:—

1. In a torpedo, the combination of an air flask, a stove therein provided with air inlet openings located underneath the center of said stove, a pipe connected to said stove 70 near its top and adapted to lead compressed air from said stove to the engines, said stove being completely closed except for said openings and said air pipe, and means for heating the air in said stove, substantially as described.

2. In a torpedo, the combination with the air flask, of a stove therein provided with air inlet openings located below its center, a pipe connected to said stove near its top and 80 adapted to lead compressed air from said stove to the engines, said stove being completely closed except for said air inlet openings and said pipe, a burner located within said stove, and means for regularly supplying 85 fuel to said burner, substantially as described.

3. In a torpedo, the combination with the air flask, of a stove, provided with openings, mounted in said air flask, and having a depression at its bottom, a pipe leading from said stove to the engines through which all the air for operating the engines must pass, a burner located in the depression at the bottom of said stove, and a plurality of fuel receptacles located at different heights and connected to said burner, substantially as described.

4. In a torpedo, the combination with the air flask, of a stove located therein and supported by said flask, said stove being provided with holes for the entrance of air thereinto, and with a depression at its bottom, a burner provided with radial holes located in said depression, fuel receptacles arranged at 105 different heights, all connected with said burner, and an air pipe leading from said stove to the engines, substantially as described.

5. In a torpedo, the combination of a plurality of receptacles arranged at different levels, a burner, connections between said receptacles and said burner, a depressed portion in the torpedo casing, connections between said depressed portions and the tops of 115 the respective fuel receptacles, and a plug adapted to open or close all of said last named connections, substantially as described.

6. In a torpedo, the combination of a stove provided with openings for the entrance of air thereinto, a pipe for conducting air from said stove to the engines, a burner located in the lower part of said stove, a plurality of receptacles arranged at different levels, a pipe connected to said burner and to all of said receptacles, and a valve in said pipe, substantially as described.

7. In a torpedo, the combination with the

air flask thereof, of a stove centrally located in said air flask and provided with openings for the entrance of air thereinto, a pipe adapted to deliver air from said stove to the engines, a jet burner located in said stove near the bottom thereof, a plurality of fuel receptacles arranged at different levels, connections between said receptacles and said

burner, a valve in said connections, and igniting means, substantially as described. 10

In testimony whereof, I affix my signature, in presence of two witnesses.
